LUBRICATION SYSTEM FOR INTERNAL COMBUSTION ENGINES

Floyd F. Kishline, Birmingham, Mich., assignor to Graham-Paige Motors Corporation, Detroit, Mich., a corporation of Michigan

Application April 23, 1937, Serial No. 138,539

6 Claims. (Cl. 184—6)

This invention relates to lubrication systems for internal combustion engines, the principal object being the provision of a simple and effective system of this type.

Objects of the invention include the provision of a lubricating system for an internal combustion engine comprising a pump having a main and an auxiliary discharge duct each of which serves to feed independent lubricating systems for different parts of the engine; the provision of a new and novel mounting for the lubricating pump of an internal combustion engine; the provision of a new and novel arrangement of oil feed ducts for the lubrication system of an internal combustion engine; the provision of a new and novel construction for eliminating entrapped air from the lubricating ducts of an internal combustion engine; the provision of a new and novel means insuring ample lubrication of the pistons of an internal combustion engine upon initiation of operation thereof from a cold condition; the provision of a new and novel means for cooling the lubricant in an internal combustion engine; the provision of a new and novel lubricating system for an overhead valve type of internal combustion engine; the provision of a novel lubricating system for an overhead valve type of internal combustion engine employing automatically adjustable valve tappets; and the provision of a construction as above described in which means are provided for eliminating the passage of air bubbles to the automatically adjustable valve tappets.

The above being among the objects of the present invention the same consists in certain novel features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Figure 1 is a partially broken, partially sectioned side elevational view of an internal combustion engine;

Fig. 2 is a slightly enlarged vertical sectional view taken transversely through the engine shown in Fig. 1 as on the line 2—2 thereof;

Fig. 3 is a still further enlarged fragmentary vertical sectional view taken transversely of the engine shown in Fig. 1 as on the line 3—3 thereof;

Fig. 4 (Sheet 1) is an enlarged vertical sectional view taken longitudinally through the pis-

ton oiling gallery shown at the righthand side of the engine in Fig. 2 and as on the line 4—4 thereof;

Fig. 5 (Sheet 1) is an enlarged fragmentary horizontal section view taken on the line 5—5 of Fig. 1, illustrating the means provided for lubricating the cam shaft driving sprocket and chain;

Fig. 6 (Sheet 2) is an enlarged vertical sectional view taken transversely of the engine 10 as on the line 6—6 of Fig. 1 and particularly through the cylinder head and associated parts thereof; and,

Fig. 7 (Sheet 3) is an enlarged fragmentary horizontal sectional view taken on the line 7—7 of Fig. 2, illustrating the oil draining groove or ditch formed in the upper face of the cylinder head for the purpose of carrying away surplus oil therefrom.

Referring to the drawings, an internal combustion engine of the multi-cylinder overhead valve type is illustrated as having a cylinder block indicated generally at 10. The cylinder block 10 comprises a crankcase 12 supporting a plurality of vertically arranged in line cylinders 14 surrounded in a conventional manner by a water jacket 16 spaced outwardly thereof to provide the usual water or other cooling liquid space 18 surrounding all of the cylinders 14. It will be particularly noted from an inspection of Fig. 3 that the space 18 extends downwardly to the extreme bottom end of the cylinders 14.

As best brought out in Figs. 1 and 2 the lower face of the crankcase 12 is formed to provide a plurality of bearing halves 20 in which the main journals of the crank shaft 22 are rotatably received and maintained in place by caps 24 secured in place for the most part by conventional screws 26 except in the case of the cap for the rear main journal, the specific construction of which is illustrated in Fig. 2 and which will be discussed in detail later.

Each cylinder 14 slidably receives a piston 28 which is connected to the corresponding throw of the crank shaft 22 by means of a connecting rod 30 in a conventional manner. The lower face of the crankcase 12 is closed by a conventional oil pan 32 secured in place in a conventional manner.

The top of the cylinder block 10 is closed by a cylinder head indicated generally at 40. The cylinder head 40 is secured to the cylinder block 10 by means of studs 42 and nuts 44, the nuts 44 being accessible by removing covers 46 and 48, covering openings 50 and 52 respectively in

the opposite sides of the cylinder head leading into the water cooling spaces 54 thereof. This particular feature forms no part of the present invention but forms the subject matter of my co-pending application for Letters Patent of the United States for improvements in Internal combustion engine, filed August 4, 1937, Serial No. 157,397.

Over each cylinder 14 the lower face of the cylinder head 40 is formed to provide a combustion chamber 56 the particular construction and arrangement of which forms no part of the present invention.

The cylinder head 40 is also interiorly formed to provide exhaust passages 58 as shown in Fig. 3 and intake passages 60 as partially shown in Fig. 2, which passages communicate with the respective combustion chambers 56 and such communication is controlled by conventional 20 downwardly opening valves 62 each slidably received in a conventional form of valve stem guide 64 suitably supported in the cylinder head. Conventional valve springs 66 are arranged in conventional manner to constantly urge the valve 25 64 towards closed position. Each combustion chamber 56 is provided with a spark plug 67 received in a well 68 formed in the cylinder head above each combustion chamber, the wells 68 opening onto the upper face of the cylinder head 40 and being closed against the entrance of 30 dust, dirt or other foreign material by means of a removable closure 69 suitably formed, of course, for the passage of the usual ignition cables (not shown) to the various spark plugs 67.

Seated upon the upper face of the cylinder head 40 in offset relation with respect to the longitudinal center line of the cylinder head is a valve tappet housing indicated generally at 70 which extends the full length of the cylinder 40 head and is provided in its length with a plurality of bores 71, as best shown in Fig. 3, one in axial alignment with each of the valves 62, and in each of the bores 71 is vertically slidably received a valve tappet 72. In the broader aspects of the present invention these valve tappets 72 may be of any suitable or conventional construction but in the more limited phase of the present invention such valve tappets are of the automatically adjustable hydraulic type which, for instance, may be of the same general principles of construction as shown in U. S. Letters Patent No. 2,051,232, issued August 18, 1936 to Carl Voorhies. A plurality of bearing blocks 74 are received upon the upper surface of the tappet housings 70 and, as illustrated in Fig. 6, are secured in place to the tappet housings 70 and the tappet housing 70 secured in place to the cylinder head 40 by means of vertically extending studs 76 extending downwardly through the bearing blocks 74, tappet 60 housing 70 and the lower ends of which are threadably secured in the cylinder head 40, nuts 78 being received on the upper ends of the studs 76. It will also be understood from an inspection of Fig. 6 that the studs 76 and cooperating nuts 78 also serve to secure the two halves of the various bearing blocks 74 in assembled relation with respect to each other.

A cam shaft 80 is rotatably received by the various bearing blocks 74 and is provided along its length with a plurality of cams 82 in accordance with conventional practice, there being one such cam 82 for each valve tappet 72 and arranged in cooperating relationship thereto. The cam shaft 80 is provided at its forward end with a sprocket 75 86 and the forwardly projecting end of the crank-

shaft 22 is provided with a similar sprocket 88 of half the diameter of the sprocket 86 and the two sprockets 86 and 88 are drivingly connected to one another by means of a conventional type of silent chain 90, thereby causing the cam shaft 80 to be driven at half the speed of the crankshaft 22. As illustrated in Fig. 1 the sprockets 86 and 88 project beyond the forward face of the cylinder block 10 and are enclosed in an oil tight housing including a flat plate 92 suitably secured to the flat front end wall of the cylinder block 10 and a chain housing cover 94 of pan-like formation sealed at its marginal edges to the plate 92. A cover 95 is provided over the cam shaft 80 and cooperating parts and is suitably sealed to the upper face of the tappet housing 70 to prevent the escape of oil therefrom.

As indicated in Fig. 2 a water pump 96 is suitably supported at a side of the engine and may be driven therefrom in any suitable or conventional manner. The water pump 96 is provided with a main discharge connection 98 and an auxiliary discharge connection 100 and is provided with a single inlet connection 102 which may be connected to a conventional radiator (not shown) in any suitable or conventional manner. The main discharge connection 98 through which the greater proportion of the cooling water is discharged from the pump is connected directly into the cover 48 on the side of the cylinder head 40 and which cover forms a water gallery extending longitudinally of the cylinder head 40 and from which the water flows directly into the water spaces 54 in the cylinder head 40.

The smaller volume of cooling water discharged through the connection 100 passes through a hose 104 and connection 106 into the interior of a hollow protuberance 108 formed on the side of the cylinder block 10 and interiorly in open communication with the water containing spaces 18 formed between the cylinders 14 and water jacket 16. The water which is introduced into the cylinder block through the connection 106 flows through the spaces 18 and then passes upwardly into the water containing spaces 54 in the cylinder head 40 through communicating passages 110 formed in the upper wall of the cylinder block 10 and the lower wall of the cylinder head 40, as illustrated in Fig. 3, in a conventional manner, and there commingles with the water discharged from the pump 96 through the passage 98 directly to the cylinder head and such commingled water is then discharged from the cylinder head to the radiator in a conventional manner (not shown).

An oil pump indicated generally at 120, best shown in Fig. 2, is located adjacent the bottom of the oil pan 32 at the rear end thereof. It comprises a casing 122 and a bottom cover 124 forming a housing for a pair of intermeshing gear elements 126 and 128 cooperating with each other and the walls of the housing to provide a pump of generally conventional construction. The pump 120 is supported by means of an upward extension or bracket 129 terminating at its upper end in a flange 130 which is secured to the lower face of the rearmost bearing cap 24 for the crankshaft 22 by means of screws 132.

The cap 24 for the rear main bearing 20 for the crankshaft 22, instead of being secured to the crankcase 12 by the bolts 26 previously described, in this instance is secured to the crankcase 12 by means of a pair of screws 134 and 136 which extend upwardly through the rear cap 24 from the bottom face thereof on opposite sides of the cor- 75

responding crankshaft journal and their upper ends are threaded into suitable openings provided in the crankcase for their reception. The screw 136 is hollow throughout its entire length and the pump casing 122 is provided with an upwardly extending boss 138 the upper end of which is formed to be piloted with a relatively close fit within the lower end of the bore of the screw 136. The cylinder block 10 and cylinder head 40 are provided with vertically extending bores 140 and 142 respectively in axial alignment with the screw 136 and extending downwardly therethrough is a hollow drive shaft 144 which extends downwardly through the boss 138 on the pump casing 122 in which it has suitable bearing and projects downwardly into the interior of the pump 120 axially of the gear 128 which is non-rotatably mounted upon the lower end thereof so as to be driven thereby. The upper end of the hollow shaft 144 is formed to provide a tongue and groove driving connection with the lower end of a stub shaft 146 rotatably mounted in the valve tappet housing 70 in axial alignment therewith. A sleeve 148 fixed to the lower end of the stub shaft 146 serves to maintain the co-operating ends of the shafts 144 and 146 in axial alignment. The upper end of the stub shaft 146 projects upwardly above the upper face of the valve tappet housing 70 and is there non-rotatably provided with a spiral gear 150 lying in meshing relationship with a co-operating gear 152 fixed against relative rotation to the rear end of the cam shaft 80. Accordingly, rotation of the cam shaft 80 causes a corresponding rotation of the shafts 146 and 144 and, accordingly, the gears 126 and 128 in the oil pump 120, thereby to cause the oil pump to exercise its pumping effect.

The supporting bracket 129 for the oil pump 120 is drilled out to provide a main discharge passage 160 in communication with the pressure side of the pump gears 126 and 128. The passage 160 communicates with a passage 162 formed in the cap 24 for the rear main crankshaft bearing and which passage 162 leads to an annular passage 164 formed in such cap around the lower end of the screw 134, and the lower end of which passage 164 is closed by the head of the screw 134. The screw 134 is hollow from a point adjacent its head through the opposite end thereof and holes 166 drilled through its walls within the height of the annular passage 164 provide communication between its hollow interior and the annular chamber 164. The crankcase 12 is interiorly formed to provide a passage 168 in communication with the hollow interior of the screw 134 and extending vertically therefrom to an oil gallery 170 formed, as best shown in Fig. 3, in the water jacket 16 on the corresponding side of the engine and extending the full length of the cylinder block 10 above the lower ends of the cylinders 14. At points in the length of the gallery 170 corresponding to the position of the main crankshaft bearings 20, with the exception of the rear main bearing 20 only, the crankcase is formed to provide a downwardly and inwardly directed duct or passage 172, as best shown in Fig. 2, connecting the gallery 170 with the corresponding journals of the crankshaft received within the corresponding bearings 20 so as to provide an ample flow of lubricant to such bearings. In the case of the rearmost bearing 20, the cap 24 therefor is provided with a passage 174 connecting the passage 162 directly with the crankshaft journal received by such bearings in order to provide it with a proper and sufficient

amount of lubrication. Any suitable or conventional means, not shown, may be provided for conducting a portion of the oil fed to the bearings 20 to the crank pins of the crankshaft 22 in order to lubricate the lower bearings of the connecting rods 39.

A laterally outwardly extending passage 176 communicates with the oil gallery 170 and in turn communicates with a vertically extending passage 178 extending downwardly therefrom and discharging into the oil pan 32 through the lower face of the crankcase 12. The passage 176 comprises two different portions of different diameters forming a shoulder 180 between them and this shoulder serves as a seat for an oil pressure relief valve 182 constantly urged towards its seat by means of a coil spring 184 constantly maintained under compression between the valve 182 and the plug 186 closing the outer end of the bore 176. It will be noted that the shoulder 180 is located in the bore 176 intermediate the gallery 170 and the passage 178 so that only when the pressure of the oil in the gallery 170 exceeds the pressure required to overcome the spring 184 is any oil permitted to pass the valve 182 and return to the passage 178 to the oil pan 32.

It is to be particularly noted that portions of the walls of the bores 168 and 178 are completely surrounded by water introduced into the water jackets 16 for the cylinders through the discharge connection 100 of the water circulating pump 96 and at a point at which the water has not yet had an opportunity to be materially heated by the walls of the cylinders 14. In the case of the walls for the bore 178 in particular these are located within the protuberance 108 where no condition exists that would tend to heat the water in any respect. Additionally, the oil gallery 170 being formed in the water jacket 16 itself has one side of its wall exposed to the air exteriorly of the engine and the other half of such wall exposed to direct contact with the cooling water within the spaces 18 formed between the water jacket 16 and the cylinders 14. Consequently all of these passages are so constructed as to be subjected to the cooling effect of the cooling water employed for cooling the engine and thus receive a material cooling effect from such cooling water which is, of course, highly desirable if not necessary in high speed modern internal combustion engines. Moreover this cooling effect is obtained at substantially no added cost as compared to conventional constructions not provided with special oil cooling means.

It is generally recognized as desirable to provide means for forcing a quantity of lubricant to the walls of the cylinders and pistons of an internal combustion engine immediately upon initiation of operation thereof so as to obviate the danger of scuffing or scoring the walls of the pistons and cylinders particularly in cold weather. In accordance with the present invention means are provided for effecting such lubrication in the following manner. As best illustrated in Figs. 1 and 2 an oil passage 200 is formed in the rear wall of the water jacket 16 and extending across the width of such wall. One end of the passage 200 is in open communication with the oil gallery 170 and at its opposite end it communicates with an angularly extending passage 202 which lies in open communication with an oil gallery 204 formed in the water jacket 16 on the opposite side of the engine from the oil gallery 170 and extending substantially the full length of the cylinder block 10.

Referring now to Fig. 4 which is the longitudinal section taken through the oil gallery 204 it will be noted that the oil gallery is of two diameters forming a shoulder 206 therebetween, the enlarged portion being relatively short and being located rearwardly of the centerline of the rear-most cylinder 14. A tube 208 of a smaller external diameter than the internal diameter of the enlarged portion of the gallery 204 is received within the enlarged bore portion of the gallery 204 in spaced relation to the walls thereof. The righthand end of the tube 208, as viewed in Fig. 4, is outwardly flared as at 210 so as to engage the shoulder 206 as well as to interiorly provide a valve seat. The flared end 210 of the tube 208 is maintained in abutting and sealed relation with respect to the shoulder 206 by means of a nut 212 threaded into the lefthand end of the bore 204, as viewed in Fig. 4, and so formed as to pilot the corresponding end of the tube 208 as well as to urge it axially against the shoulder 206. The corresponding end of the gallery 204 is closed and sealed by means of a screw plug 214. Oil in the entrance end of the oil gallery 204 is communicated to the interior of the tube 208 by means of a plurality of holes 216 drilled through the walls of the tube 208.

Received within the elongated smaller bore portion of the gallery 204 is a rod 218 the lefthand end of which is formed to provide a valve 220 for co-operation with the seat formed by the inner wall of the flared end 210 of the tube 208. The opposite end of the rod 218 is guidingly received in the inner end of a screw plug 222 adjustably received within the righthand end of the gallery 204 as viewed in Fig. 4. Leakage of oil between the plug 222 and the walls of the gallery 204 is prevented by means of a sealing nut 224 threaded over the outwardly projecting end of the plug 222 and bearing against the corresponding end face of the walls of the gallery 204. The rod 218 at intervals in its length is provided with angularly offset pins 226 fixed with respect to the rods 218 but slidably received within the gallery 204 so as to maintain the rod 218 centrally therein without restricting axial movement thereof. The rod 218 is formed of a material having a greater coefficient of expansion than the walls of the gallery 204 so that when heated to a predetermined temperature it will be caused to lengthen axially and to bring the valve 220 into seating relation with respect to the valve seat formed by the interior walls of the flared end 210 of the tube 208, and thereby close communication between the interior of the tube 208 and the main portion of the oil gallery 204. The material from which the rod 218 may be formed may be copper, brass, aluminum or any other suitable material having a higher coefficient of expansion than the walls of the gallery 204 and the actual temperature at which the valve 220 seats to shut off communication with the interior of the tube 208 may be readily adjusted by threading the screw plug 222 either inwardly or outwardly in the gallery 204.

As best shown in Fig. 3 the oil gallery 204 forwardly of the shoulder 206 communicates with a plurality of upwardly and inwardly extending passages 230, one of which leads to the bore of each cylinder 14, so that when the valve 220 is open and the engine is operating oil fed to the gallery 204 will be fed through the various passages 230 to the bore of all of the cylinders 14 at a point therein normally swept by the corresponding pistons 28 during reciprocation thereof, thereby to provide a direct flow of lubricant to

the walls of such cylinders and pistons. The passages 230 are upwardly directed from the gallery 204 to the bores of the cylinders 14 to prevent inadvertent draining of the gallery 204 during inoperative periods of the engine and so that the flow of oil from the gallery 204 through the passages 230 to the walls of the cylinders and pistons will be instantaneous upon initiation of engine operation from a cold condition.

Although not forming any part of the present invention it is desirable, if not necessary from a practical standpoint to render this part of the system entirely effective for the purpose described, that the pistons 28, as best illustrated in Fig. 3, be provided adjacent their lower edges with a circumferential groove 232 adapted to be brought into registry with the inner end of each corresponding passage 230 at least once during each reciprocation of the piston 28 so as to insure the lubricant introduced through the passages 230 being carried around the complete circumference of the pistons. Relatively short transverse grooves 234 may also be provided in the surface of the pistons 28 in intersecting relation with respect to the grooves 232 to further aid in the distribution of such lubricant. This last feature of providing the grooves 232 and 234 in the piston 28 forms the subject matter of my co-pending application for Letters Patent of the United States for improvements in Lubrication system for internal combustion engines, filed April 19, 1937, Serial No. 137,682.

In accordance with a further phase of the present invention the wearing parts of the engine other than those heretofore described are lubricated by an independent lubricating system the supply for which, however, is furnished by the same oil pump 120 which supplies the system already described. For the purpose of supplying this second lubricating system the cap 124 of the oil pump is provided in its upper face with a groove 250 leading from the pressure side of the pump gears 126 and 128 to a point below the hollow drive shaft 144 with the interior of which it is in open communication. Accordingly, a portion of the oil discharged from the pump 120 passes through the groove 250 in the cap 124 and into the hollow interior of the drive shaft 144 where it flows upwardly therethrough and into the hollow interior of the stub shaft 146. It is preferable to provide an upwardly opening ball check valve 252 in the lower end of the drive shaft 144 so as to prevent oil in the shaft 144 from draining downwardly out of its bore during inoperative periods of the engine.

The tappet housing 70 is provided with an oil gallery 254 therein extending longitudinally thereof from end to end. The bearing bushing 256 in the tappet block 70 for the stub shaft 146 is interiorly provided with an annular groove 258 which is in constant communication with the interior of the stub shaft 146 through drilled openings 260 and is also in open communication with the gallery 254 through openings therethrough directly connecting the groove 258 with the oil gallery 254.

The bushing 256 which projects upwardly above the upper face of the tappet housing 70 and serves as a thrust member for the gear 150 is provided adjacent its upper end with a hole 262 through the wall thereof directed towards the face of the gear 152. The stub shaft 146 is provided with an opening 264 in a wall thereof in the same radial plane as the opening 262 so that once during each rotation of the stub shaft 146

the openings 262 and 264 are brought into registry with each other to thus permit the discharge of a small amount of oil through these registered openings directed against the face of the gear 152, thereby providing lubrication for the wearing surfaces of both the gears 150 and 152. Furthermore in view of the fact that the opening 264 is at the extreme upper end of the bore of the stub shaft 146 and a material distance above the gallery 254, any air that becomes entrapped in the oil delivered to the hollow interior of the shafts 144 and 146 naturally rises to the upper end of such bore and is discharged therefrom through the openings 264 and 262. It will be obvious that any small amounts of air that may thus be discharged through the openings 262 and 264 against the face of the gear 152 will have no material ill effects upon the lubrication of the same and, more important, at the same time it provides a construction which carries away such air bubbles from possible passage at a lower level into the oil gallery 254.

Referring now to Fig. 3 it will be noted that the bore 71 in the tappet housing 70 for each tappet 72 is connected to the gallery 254 by means of a downwardly directed passage 270 which, when the tappet is of a conventional-mechanical construction, serves to lubricate the wearing surfaces of the corresponding tappet and the bore in which it works, and where the tappets 72 are of the automatically adjustable hydraulic type these passages 270 further serve to provide a constant supply of lubricant under pressure to such valve tappets as is necessary in such cases. In the latter case the tappets 72 are preferably provided with a circumferential groove 272 in constant communication with the corresponding passage 270 and each tappet is provided with a suitable passage such as the passages 274 for carrying oil from the corresponding groove 272 to its interior.

Referring now to Fig. 6 it will be noted that the gallery 254 intersects the openings in the valve tappet housing 70 through which one of the downwardly extending studs 76 for each bearing block 74 passes, and that the upper end of this opening in the valve tappet housing 70 is enlarged to provide an annular oil passage 276 about the corresponding stud 76 in open communication with the gallery 254. The lower half of each bearing block 74 is provided with an oil passage 278 connecting the corresponding annular passage 276 with the corresponding bearing surface for the cam shaft 80. It will be noted that the passages 276 and 278 extend upwardly from the gallery 254 whereas the passages 270 for conducting oil from the gallery 254 to the tappets 72 extend downwardly from the gallery. This arrangement is provided for the reason that it is highly desirable to prevent any air from being carried to the tappets 72 where such tappets are of the automatically adjustable hydraulic type. Accordingly, should any air bubbles become entrapped in the supply of oil from the oil pump 120 and fail to be discharged from the upper end of the stub shaft 146 as heretofore described and be carried into the gallery 254, such air bubbles will be carried to the upper strata of the oil flowing through the gallery 254 and eventually will be discharged therefrom by passing upwardly through the passages 276 and 278 to the various bearings of the cam shaft 80 while the oil which is fed to the tappets 72 is taken from the lower part of the gallery 254 and at which point the oil will be free of entrapped air bubbles. The rubbing surfaces between the

tappets 72 and the cams 82 will be amply lubricated by the oil vapor which will usually fill the cover 95 as well as by particles of liquid oil escaping from between the tappets 72 and their corresponding bores 71 in which they work and from the various bearing blocks 74 around the cam shaft 80.

The excess oil which thus escapes from the wearing surfaces of the tappets 72 and cam shaft 80 will readily drain downwardly through the tappet housing 70 to the upper face of the cylinder head 40 below the housing 70. It has been found that if any material amount of such oil is permitted to build up around the lower ends of the valve springs 66 it will be picked up by such valve springs and carried upwardly and become deposited upon the exposed portions of the stems of the valves 62 where it will have a tendency to be drawn downwardly between the valve stems and their guides and on to the heads of the valves 62 as well as into the corresponding combustion chambers 56. This is undesirable for the reason that such oil in these locations will be carbonized by the heat to which it is subjected and will have a tendency to form carbon deposits upon the valves and in the combustion chamber and on the pistons. Accordingly, in order to eliminate the possibility of this undesirable occurrence the upper face of the cylinder head 40 below the tappet housing 70 is provided with a trough or ditch-like depression 280 the bottom of which is located below the lower end of the valve springs 66. As best illustrated in Fig. 7 the groove or ditch 280 is of a sinuous character winding back and forth between the valves 62 over the length of the cylinder head 40. At its rear end the groove or ditch 280 opens into the bore 142 formed in the cylinder head 40 for reception of the shaft 144 and consequently any accumulation of oil in the groove or ditch 280 at the rear end thereof may drain downwardly into the crankcase through the bores 142 and 140.

As best indicated in Fig. 1, at the forward end of the engine the ditch or groove 280 stops short of the forward face of the engine and communicates with the chain housing through a downwardly and forwardly extending passage 282 formed in the cylinder head 40 which leads to an opening 284 in the plate 92 forming one wall of the chain housing. Accordingly, oil at the forward end of the groove or ditch 280 may drain downwardly through the opening or passage 282 and through the opening 284 into the interior of the chain housing 92-94 the lower end of which is in open communication with the interior of the oil pan 32. While the flow of oil through these last mentioned passages might be relied upon for suitably lubricating the sprockets 86 and 88 and connected chain 90, preferably a more positive means is provided for this purpose. This is brought out in Figs. 1 and 5 in which it will be noted that the forward end of the oil gallery 254 in the tappet housing 70 is slightly enlarged and receives therein a disc or button 290 having a relatively small central orifice 292. The front plate 92 is provided with an enlarged opening 294 in axial alignment with the orifice 292. The orifice 292 is so positioned that oil under pressure in the gallery 254 will be discharged therefrom against the sprocket 86 from which the oil will be carried onto the chain 90 and thence to the face of the sprocket 88 in sufficient quantities to properly lubricate these parts. It will be understood, of course, that the rear end of the

oil gallery 254 is closed except for its communication with the hollow interior of the stub shaft 146 as previously described.

From the foregoing description it will be understood that lubrication of the various parts of the engine described is accomplished through two more or less independent lubricating systems both of which are supplied by a common pump 120. The lubricating system for the crank shaft and other heavily loaded bearing parts which require the greatest amount of lubrication is accomplished in the main by supplying such oil to the longitudinally extending gallery 170 from which it is conducted to the various co-operating wearing parts. As previously described a major portion of this main lubricating system is so positioned, constructed and arranged that its various oil passages are subjected to the cooling effects of the water circulation system for the engine thereby to aid in the efficient cooling of such lubricant. The oil which is conducted through the passage 200 across the rear end of the engine to the gallery 204 is also cooled by reason of its being carried through the water jacket proper of the engine, but inasmuch as the valve 220 is preferably adjusted to permit a flow of oil through the gallery 204 to the bores of the various cylinders 14 only during initial operation of the engine from a cold start, the cooling effect for this reason may be more or less negligible. However, it will be understood that the valves 220 may be adjusted to permit a small continued flow of lubricant to the bores of the cylinders during normal operation of the engine and in such case a material cooling effect of the oil will be realized from this part of the system.

The screw plug 222 which controls the axial position of the rod 218 and consequently the valve 220 is preferably so adjusted that when the engine is cold the rod 218 will shorten sufficiently in length to unseat the valve 220 but when the engine and the water within the spaces 18 surrounding the cylinders 14 have reached a normal operating temperature, or have approached such temperature, the length of the rod 218 will increase sufficiently to cause the valve 220 to be seated against the end of the tube 208 and thus shut off further flow of oil to the gallery 204. By this means an automatic arrangement is provided whereby when the engine is started up from a cold condition an ample and immediate flow of oil to the wearing surfaces between the bores of the cylinders 14 and the pistons 28 will be provided to effectively prevent scuffing or scoring of either the pistons or the cylinders and as soon as the engine has warmed up sufficiently to insure lubrication of these surfaces by a splash of oil from the connecting rod bearings or other normal or conventional means, further lubrication of the cylinders and pistons from the gallery 204 is terminated.

It will also be understood from the foregoing description that the other lubricating system which may be termed more or less auxiliary to the main system first described is so constructed and arranged as to provide an ample supply of lubricant to the lesser wearing surfaces of the engine and that the construction and arrangement of this second lubricating system is such as to efficiently eliminate the carrying of air bubbles to any operating part where their presence might have an ill effect, and also that the elimination of the presence of such air bubbles is accomplished in such a manner as to have no material effect on the proper lubrication of the

desired parts. On the whole it will be observed that the lubrication of all of the wearing parts of the engine is accomplished in a simple, efficient and highly satisfactory manner.

Formal changes may be made in the specific embodiment of the invention described without departing from the spirit or substance of the broad invention, the scope of which is commensurate with the appended claims.

What I claim is:

1. In combination with an internal combustion engine having an oil pan at the bottom thereof, a cam shaft at the top thereof and valve tappets at the top thereof operable by said cam shafts, an oil pump in said oil pan, a hollow rotatable shaft extending from the lower portion of said engine to a point adjacent said cam shaft and having its bore closed at its upper end, means for driving said hollow shaft, means for introducing oil from said oil pump into the interior of said hollow shaft, said hollow shaft having a passage through a side wall thereof adjacent its upper closed end, stationary means surrounding the upper end portion of said hollow shaft and having a passage therethrough registerable with said passage in said shaft during rotation of said shaft therein, a horizontally extending oil conduit adjacent the top of said engine, other conduits connecting said conduit with said tappets, and means effecting communication between the first mentioned conduit and the interior of said hollow shaft at a point downwardly spaced from said passage whereby air bubbles carried by the oil introduced into said hollow shaft will tend to flow upwardly beyond the point of intercommunication between the interior of said hollow shaft and said first mentioned conduit to the upper end of said hollow shaft and will be ejected therefrom through said registerable passages.

2. In combination with an internal combustion engine having an oil pan in the bottom thereof, a cam shaft at the top thereof, and automatically adjustable tappets of the hydraulic type operable by said cam shaft, a conduit extending from a point adjacent said oil pan to a point adjacent said cam shaft, means for introducing oil under pressure into the lower end of said conduit, means closing the upper end of said conduit, means surrounding the upper end of said conduit, the last mentioned means and said conduit being relatively rotatable and having passages in the walls thereof registerable with each other during relative rotation, a longitudinally extending conduit at the top of said engine adjacent said tappets connected with said tappets whereby to provide a supply of oil thereto, means intercommunicating the last mentioned conduit with the first mentioned conduit at a point below said passages whereby air bubbles in the oil supply to the first mentioned conduit at the lower end thereof will tend to pass upwardly in said first mentioned conduit beyond the point of intercommunication between said conduits and be discharged from said first mentioned conduit through said registerable passages thereby to provide said second mentioned conduit and said tappets with a supply of oil free of entrapped air.

3. In combination with an internal combustion engine having an oil pan at the bottom thereof, a cam shaft at the top thereof, bearings for said cam shaft, automatically adjustable valve tappets of the hydraulic type below said cam shaft and actuatable thereby, a conduit extending from said oil pan to a point adjacent said cam shaft, means for introducing oil under

5 pressure into said conduit, a second conduit in the top portion of said engine and located between the axis of said cam shaft and the lower ends of said tappets, means intercommunicating said conduits, auxiliary conduits extending downwardly from said second conduit for supplying oil therefrom to said tappets, other auxiliary conduits extending from said second conduit upwardly to the bearings for said cam shaft, and 10 means for intermittently discharging oil and entrapped air from the interior of the first mentioned conduit at a point therein above the point of intercommunication between said first and second mentioned conduits.

15 4. In combination with an internal combustion engine having a plurality of cylinders and pistons reciprocable therein, an oil gallery extending longitudinally of the engine, conduits connecting said oil gallery with the bores of said cylinders, a valve seat adjacent one end of said gallery, an elongated valve member in said gallery formed of a material having a higher coefficient of expansion than the material forming the walls of said gallery, and means for feeding lubricating oil under pressure to said gallery between 20 said valve seat and the corresponding end of said gallery.

25 5. In combination, with an internal combustion engine having a plurality of cylinders and means for circulating a cooling fluid around said cylinders, a lubricating oil gallery extending longitudinally of the engine with a wall portion thereof bathed by said cooling fluid, said engine being provided with ducts providing communication between said gallery and the bore of each 30 of said cylinders, means for introducing lubricating oil under pressure into said gallery, a valve in said gallery for controlling the flow of lubricating oil thereinto, and means comprising an 35 elongated member adjustably mounted in said

5 gallery for controlling the position of said valve, said elongated member having a higher co-efficient of expansion than the walls of said gallery whereby when said elongated member is heated by said oil therein after said engine is started from a cold condition said valve will be moved towards a position to restrict the flow of lubricating oil into said gallery.

10 6. In combination with an internal combustion engine having a plurality of cylinders arranged in line and means for circulating cooling fluid over the exterior surfaces of said cylinders, an oil gallery extending longitudinally of the engine and arranged in heat conducting relationship with respect to said cooling fluid, a shoulder formed 15 in said gallery adjacent one end thereof by enlarging said end of said gallery, a tube positioned in said enlarged end of said gallery with the exterior surfaces thereof in generally spaced relationship with respect to the inner walls of said 20 end, the inner end of said tube being flared to provide axial engagement thereof with said shoulder and to provide a valve seat interiorly of said flared end, means for maintaining said tube against said shoulder, means for introducing 25 lubricating oil under pressure into said gallery between said tube and the walls of said gallery, said tube having openings through the walls thereof to provide for the flow of said oil into the interior of said tube, means at the opposite 30 side of said gallery adjustable axially thereof, an elongated member in said gallery abutting said means at one end thereof and having a valve at the opposite end thereof in cooperative relationship with respect to said valve seat, said elongated member having a higher co-efficient of 35 expansion than the walls of said gallery whereby increase in temperature of oil in said gallery will cause said valve to approach said valve seat.

FLOYD F. KISHLINE. 40
